(57) CLAIM

I claim the ornamental design for a bar tools storage and display shelf, substantially as shown and described.

DESCRIPTION

FIG. 1 is a perspective view of a bar tools storage and display shelf in accordance with our new design;

FIG. 2 is a perspective view thereof;

FIG. 3 is a front view thereof;

FIG. 4 is a back view thereof;

FIG. 5 is a side view thereof;

FIG. 6 is a side view thereof;

FIG. 7 is a top view thereof; and,

FIG. 8 is a bottom view thereof.
